(57) **CLAIM**

The ornamental design for a combined tabletop with hardware, as shown and described.

DESCRIPTION

FIG. 1 is a top plan view of a combined tabletop with hardware, showing our new design;

FIG. 2 is a right side elevation view of the combined tabletop with hardware of FIG. 1, the left side elevation view is identical thereto;

FIG. 3 is a front view of the combined tabletop with hardware of FIG. 1, the rear view is identical thereto; and, FIG. 4 is a perspective view of the combined tabletop with hardware of FIG. 1.

The broken lines in the figures illustrate portions of the combined tabletop with hardware that form no part of the claimed design.
